TYPEWRITING MACHINE

Rogelio Padin, Florida, Argentina, assignor to
 Underwood Elliott Fisher Company, New York,
 N. Y., a corporation of Delaware

Application October 28, 1940, Serial No. 363,140

5 Claims. (Cl. 197—179)

This invention relates to work-sheet-tabulating mechanism for typewriting and bookkeeping machines.

A work sheet may be divided into a multiplicity of tabulating columns, say, a series of fifty successive columns each including three or more letter spaces as exemplified by the columns *k* of the work sheet at Figure 5.

A given line of typing done on the work sheet may include entry in a selected one or more of said columns. But column selection may vary for every line in that entries will not necessarily be in the same column or columns for different lines.

An object of the invention, therefore, is to provide tabulating-stop mechanism and controls therefor whereby for each line the appropriate column or columns may be selected and the tabulating carriage may be moved directly to a selected column without stopping at intermediate columns.

A stop rack including a stop for each of said multiplicity of columns is preferably mounted on the carriage which travels laterally for tabulating. Each stop is settable from a normally retracted position on the rack to an effective position wherein it may be engaged by a counterstop on the main frame. The counterstop is projectible into the path of the set rack-stop by operating a conventional tabulating key which also serves to release the carriage for an ensuing spring-driven tabulating jump which is gaged by means of the set rack-stop and counterstop.

A further object is to provide for facilitating the selective setting of the rack-stop or stops according to the requirements of a given line of typing. This may be accomplished by providing a key-operable stop-setter for each of the multiplicity of rack-stops. There are provided, therefore, according to the present instance, fifty stop-setters with their stop-setting keys in a conveniently accessible array on the carriage.

A further object is to provide for automatic restoration of a set rack-stop after the latter has served its purpose during the typing of a line. Such restoration is necessary in order that a rack-stop setting suitable for one line will not stand for a succeeding line which may require a different rack-stop setting. The rack-stop restoration is made automatic so as not to require attention of the typist whose work, therefore, in a tabulating operation is limited, as far as said fifty columns are concerned, to merely selecting and operating a stop setter and operating the usual

counterstop-projecting-and-carriage-releasing tabulating key.

Another object is to effect the automatic rack-stop restoration by using a simple, inexpensive device in combination with the rack stops.

Another object of the invention is to correlate structure embodying the aforesaid rack-stops and stop-setters with an existing design of bookkeeping machine such as exemplified in H. L. Pitman Patent No. 2,160,487, dated May 30, 1939. In such machine, the carriage mounts a plurality of column units each of which controls computing mechanism.

Another object is to provide for readily placing the stop setter at different letter space positions of the carriage in accordance with variations in the column spacing of the stops used with the rack. In respect of this, the rack may include a stop at each letter space so that it will not be necessary to shift rack-stops along the rack but merely to shift the stop-setter according to any desired change of column-spacing intervals.

With these and other objects, features, and advantages in view, the invention consists of novel features of construction and combinations of parts as set forth in the following description and the appended claims.

In the accompanying drawings:

Figure 1 is a perspective illustrating details of a stop-restoring cam and support.

Figure 2 is a perspective of the array of stop-setters, supports and stops, the view being condensed by showing only the end portions of the array, the intermediate portion being similar.

Figure 3 is a cross-sectional side elevation of the carriage and tabulating-stop-structure.

Figure 4 is a laterally condensed plan view of the carriage and tabulating-stop-structure.

Figure 5 is a laterally condensed diagram of a work sheet including numerous selective columns *k*.

Typing carriage *C* has a frame *15* which runs upon a front rail, not shown, and a rear rail *16* on main frame *F* of the machine. A revoluble platen *18* is journaled in side members *19* of the carriage. The carriage also includes the usual upward and rearwardly sloping paper table *20* and bottom apron *21*. Pressure rolls *22* cooperate with the platen to move a work sheet upon rotation of the platen as by line-space mechanism, not shown. The usual type bars *11* are movable to a common printing point at the platen.

A tabulating rack *23*, of rectangular tubular section, has top and bottom walls slotted through at letter-spaced intervals to receive

plate-like tabulator stops 24. A resilient detent prong 25, Figure 3, of each stop 24 engages the top wall at the side of the rack slot to detain the stop in its ineffective, retracted, position or in its effective, projected, position in the rack, each stop being vertically movable in the rack between said positions. A shoulder 26 of each stop may engage the rack side wall to limit depression of the stop to effective position.

A counterstop-forming reed 28, in a housing 29, is vertically movable between a depressed position and a raised position in which its upper end is in the path of the effectively set rack-stops 24. Operation of a tabulating key, not shown, raises the counterstop 28 to effective position and causes release of the carriage from the usual escapement device 30 for ensuing leftward tabulating movement by the usual spring motor 31. The tabulator rack 23 and its stops 24 are substantially as shown in W. F. Helmond Patents No. 1,901,162, dated March 14, 1933, and No. 2,053,079, dated September 1, 1936. There may be either a single reed 28, or a denominational set of such reeds and corresponding denominational tabulating keys.

The carriage is also provided with one or more column units 33 and a rack frame 32 for such units substantially as shown in the aforesaid Pitman Patent No. 2,160,487. Each column unit 33 includes tappets for engaging denominational jacks 34 and register selecting cam plates 35 of computing mechanism, not otherwise shown. Said rack frame 32 for said units includes a front rack 36, a rear rack 37, and side brackets 38 to which racks 36 and 37 are rigidly connected. Rack supporting arms or brackets 39, 40 and 41 are fixed to carriage frame 15 as by screws 42 and have upturned parts 43 to which the tubular rack 23 is secured at its front wall by screws 44. The left-hand bracket 39 presents, above rack 23, a horizontal plate 45 having a notch 46 and, similarly, the right-hand bracket 41 presents a plate 47 having a notch 48. Said notches 46, 48 receive studs 49 of the rack frame 32 and the latter has a latch lever 50 releasably engaging a stud 51 of bracket plate 47, rack frame 32 being thus detachably supported by the carriage with its front rack 36 adjacent and behind the tubular rack 23. The rear end of each column unit 33 runs in a trackway 52 while the unit traverses a computing zone.

Some of the tabulating stops 24 may be set permanently in effective position for a given work sheet form. But others of the stops 24 are settable selectively for each line of typing on the form.

For example, referring to Figure 5 which represents a work sheet record of telegraph and cable traffic, each of the columns beginning with the date column and up to and including the Words column is represented by a permanently set stop 24 in the rack. But in any given line, an entry following the Words column may fall within any one of the numerous succeeding columns *k* each of which represents a different country and the entry therein represents the number of words dispatched.

For each of such succeeding columns *k*, there is provided a stop-setter in the form of plunger 54 standing above the appropriate stop 24. The work sheet columns corresponding to said plungers accommodate, say, up to three letter spaces each with the exception of certain wider columns which represent countries, such as U. S. A., having a comparatively large volume of

traffic. The stop-setting plungers 54 are spaced according to these narrow and wide column spacings of columns *k*. Upper and lower guide and spacing combs 56 for the stop setting plungers 54 are in the form of flanges of a vertical plate 55 and have slots 57 at letter-spaced intervals. The plungers 54 are spaced in such of the slots 57 as will distribute the plungers according to the required column spacing. Each plunger has at its top a finger key 58.

To avoid crowding the keys 58, the latter are staggered by arranging them in upper and lower rows, each row comprising the keys of alternate plungers. The lower ends of all the plungers 54 abut or rest upon the top edges of their corresponding stops 24. The plungers having keys 58 in the lower row are of course shorter, say, by one inch, than those having the upper row keys. The plunger slots 57 of each comb open into the edge of the comb but are closed by means of a strip 59 which overlies the comb and is secured at its ends to the comb by screws 60. Each plunger is in the form of a flat reed and has a notch 61 to form upper and lower shoulders 62 opposed by the upper strip 59 to retain the plunger vertically. The upper shoulder 62 may strike the top of the upper strip to limit depression of the plunger in depressing the underlying stop 24 to its effective position. The plunger supporting plate 55 is mounted on the carriage by setting its lower comb 56 and a spacer 65 upon and securing same to the right-hand bracket plate 47 as by a screw 60, and by securing said plate 55 by a screw 67 to an upstanding extension 68 of the intermediate bracket 40.

In starting a line of typing on the work sheet, the carriage starts from a fully returned position determined by a margin stop, not shown. The carriage is tabulated by means of the permanently set stops 24 to each column up to and including the Words column. Then, according to which of the succeeding columns is to receive an entry for the instant line of typing, a plunger 54 is depressed or will have been depressed to depress the corresponding stop 24. A stop 24 having thus been set by its plunger 54, the tabulating key, not shown, is depressed causing the carriage to be tabulated to the column corresponding to the operated plunger 54. After typing in this column, and perhaps also in succeeding columns, as may be determined by depressing other plungers 54, the carriage may be returned to its starting position and the stop or stops 24 that were selectively set by means of the stop-setting plungers 54 may be restored preparatory to typing another line.

The return movement of the carriage effects such restoration of the selectively set stops automatically by the following means: A support 72 is fixed to the back of the machine frame F by screws 73 and has an arm 74 presenting at the proper location a pivot stud 7 for a stop-restoring cam 76. Said cam 76 is yieldably disposed in the path of the set stops 24 by being normally kept by a spring 77 in abutment with a stop pin 78 on arm 74. At return movement of the carriage, any one of the stops 24 that was set by means of its plunger 54 encounters and overrides cam 76 which is at this time backed by and reacts on stop pin 78, thereby causing the set stop to become restored upwardly to its ineffective position in the tubular rack. But at the movement of the carriage in tabulating direction, the set stop 24 in traversing the cam

76 merely turns the latter idly about the pivot stud 75 and away from stop pin 78 contrary to the force of the spring 77, the latter being effective to restore the cam after the stop, moving in tabulating direction, has passed the cam. The arm 74 may present the cam 76 in such position that it is in the comparatively wide space between the stop 24 for the Words column and the first selectable stop (for the U. S. A. column) when the carriage is in fully returned position as in Figure 4.

The rack frame 32 may have a column unit 33 for the Words column to control a totalizer, not shown, for totaling all the amounts typed in that column. Each of the wider selective columns *k*, such as the U. S. A. column, may also have a column unit 33 to control a totalizer, not shown, to total all the amounts typed in such column. The totals are typed at the foot of the columns by copying them from the corresponding totalizers; the totals of the narrower selective columns are usually small and may be computed mentally and then typed at the foot of these columns. A check is had by comparing the sum of totals of all the selective columns with the total of the Words column.

It may be explained that in the type of computing machine exemplified in the aforesaid Pittman patent and herein contemplated, the column unit 33 usually projects forwardly from the rack 36 to present a tabulating stop cooperative with the counterstop 28; in the present instance, however, such forward projection and its tabulating stop is omitted or cut off from each unit 33 and instead a proper one of the stops 24 is used, such stop 24 being either permanently set in effective position as for the words column or being selectively settable by its plunger 54. A tool such as the tip of a screw driver may be inserted over and may depress the stop 24 which is to be set permanently, and, similarly, a permanently set stop may be restored. Cam 76 is disposed relatively to the permanently set stops so as not to be in the path of the latter and restore same at return of the carriage.

Since the plunger combs 56 have a plunger-receiving slot 57 at each letter space within the range of selectively settable stops, the column spacing of the plungers is not fixed but may be varied as desired. By loosening the screws 60, the upper guide strip 59 may be moved backwardly to release the plungers 54 for placement in one slot or another. Said strip 59 may have oblique, elongate holes 80 for the screws 60 so that by moving the strip endwise by its finger piece 81, it is at the same time moved away from the plungers to release the latter, or toward the plungers to close the slots 57 for slidably confining the plungers. A plunger-designating scale 82 marked to represent the selective columns *k* of a particular work sheet is presented adjacent the plungers 54 by being retained in edge grooves provided by a clip 83 fixed to the front of plate 55.

The portion of the work sheet trailing or delivered from the platen may be kept clear of the scale 82 and the plunger keys 58 by being kept within a scroll-like container or guide 84, fixed to the paper table 29, to guide the trailing or delivered portion of the sheet upwardly and rearwardly from the platen and then reversely away from the scale and keys, Figure 3.

It will be seen now that, in respect to typing any line on a work sheet such as that in Figure 5, tabulating the carriage to any one of the numerous selective columns *k* requires, preparatory

to operation of the usual tabulating key, not shown, only an operation of the appropriate plunger 54 to set a corresponding stop 24. Each required subsequent restoration of the set stop is taken care of automatically by means of the returning carriage. It will also be seen that the structure is inexpensive, is applicable to existing designs of machine, and provides, in a simple way, for varying the column spacing of the plungers.

When any plunger 54 is depressed, it may continue to rest upon the top of the correspondingly depressed stop 24 and is restored upwardly by the described restoration of said stop 24.

The Figure 5 work sheet having the numerous selective columns *k* is accommodated by using a wide carriage, for example, a carriage known nominally as a 26-inch carriage. The rack structure is of corresponding width.

Variations may be resorted to within the scope of the invention and portions of the improvements may be used without others.

What is claimed is:

1. A tabulating mechanism including, in combination, a typing carriage, a frame on which said carriage is reciprocatable in tabulating and return directions, a series of column-spaced tabulating stops on said carriage selectively settable from ineffective to effective position, and a restoring cam mounted on said frame and supported yieldably in the path of the set stops so as to encounter and restore a set stop by movement of the carriage in return direction but to yield idly when overridden by a set stop at movement of the carriage in tabulating direction.

2. The combination with a typing carriage and a frame on which said carriage is reciprocatable in tabulating and return directions, of a stop-device always in effective position on said carriage for encountering a key-operable counterstop on said frame, column-spaced stops following said stop-device in series on said carriage and selectively settable from an ineffective position to a position for encountering said key-operable counterstop, whereby after a tabulating movement of said carriage is gaged by means of said stop-device, a further tabulating movement is gageable differentially according to which of said following stops is set, each of said following stops having associated therewith a stop-setter manually operable at will preparatory to said further tabulating movement in typing a line; and a restoring cam on said frame supported yieldably in the path of the set following stops to restore the latter by movement of the carriage in return direction but to yield idly when overridden by a set latter stop at movement of the carriage in tabulating direction.

3. In a carriage tabulating mechanism, the combination with a stop-rack mounted on the carriage and a series of column-spaced stops on said rack individually settable from an ineffective position to an effective position, the column-spacing of said stops being variable for different work sheet forms, of two spaced guide bars mounted on the carriage, each bar having letter-spaced guide slots covering the range of column spacing, and stop-setting plungers retained in said guide bars and variably disposable in such of said guide slots as correspond to the column spacing determined for the rack stops, each plunger being operable to set a corresponding rack stop.

4. In a carriage tabulating mechanism, the combination with a stop-rack mounted on the

carriage and a series of column-spaced stops on said rack individually settable from an ineffective position to an effective position, the column-spacing of said stops being variable for different work sheet forms, of two spaced guide bars mounted on the carriage, each bar having letter-spaced guide slots covering the range of column spacing, and stop-setting plungers retained in said guide bars and variably disposable in such of said guide slots as correspond to the column spacing determined for the rack stops, each plunger being operable to set a corresponding rack stop, each plunger mounting a finger key, and adjacent plungers being of different lengths in the direction of plunger movement to dispose the keys in two staggered rows.

5. A tabulating carriage including: a revoluble platen, a paper guide mounted behind the platen

and formed to direct the delivered part of a work sheet upwardly and rearwardly from the platen and then reversely, column-spaced tabulating stops mounted behind said guide and individually settable downwardly from an ineffective to an effective position, an upright plate mounted behind said guide and having two, upper and lower, horizontal flanges above the settable stops, upright stop-setting reeds guided for endwise movement and disposed over corresponding stops by said flanges, said reeds being surmounted each by a finger-key and being of such length that the keys are arrayed horizontally and materially above the top of said guide which serves to keep the delivered part of the work sheet clear of the keys.

ROGELIO PADIN.
